Primary Examiner — Cathron Brooks*Assistant Examiner* — Aula Soroush(74) *Attorney, Agent, or Firm* — Banner & Witcoff, Ltd.(57) **CLAIM**

The ornamental design for a shoe outsole, as shown and described.

DESCRIPTION

FIG. 1 is a front perspective view of a shoe outsole showing our new design;

FIG. 2 is a top view thereof; and,

FIG. 3 is a rear perspective view thereof.

The photographic area is claimed. The broken lines immediately adjacent to the photographic area represent the bounds of the claimed design. The broken lines showing the remainder of the shoe are for environmental purposes only and form no part of the claimed design.
